(57) **CLAIM**

We claim the ornamental design for a docking station, as shown and described.

DESCRIPTION

FIG. 1 is a top perspective view of a docking station showing our new design;

FIG. 2 is a front view thereof;

FIG. 3 is a rear view thereof;

FIG. 4 is a left side view thereof;

FIG. 5 is a right side view thereof;

FIG. 6 is a top view; and,

FIG. 7 is a bottom view.

The ornamental design which is claimed is shown in solid lines in the drawings. Any broken lines in the drawings are for illustrative purposes only and form no part of the claimed design.

1 Claim, 5 Drawing Sheets# US D760,649 S
